INVENTOR.
Robert CLOW
BY
Warren O'House,
His ATTORNEY

UNITED STATES PATENT OFFICE.

ROBERT CLOW, OF KANSAS CITY, KANSAS.

PLUMBER'S CLEAN-OUT.

1,374,189.

Specification of Letters Patent. Patented Apr. 12, 1921.

Application filed January 8, 1918. Serial No. 210,837.

To all whom it may concern:

Be it known that I, ROBERT CLOW, a citizen of the United States, residing at Kansas City, in the county of Wyandotte and State 5 of Kansas, have invented a certain new and useful Improvement in Plumbers' Clean-Outs, of which the following is a specification.

My invention relates to improvements in 10 plumbers' clean-outs.

One of the objects of my invention is to provide a plumber's clean-out with a cover which may be easily and quickly attached or detached and which will be firmly held in the 15 closed position.

A further object of my invention is to provide a plumber's clean-out of novel construction, which is simple in structure, which 20 is economical to manufacture and not liable to get out of order, and which is efficient in operation.

Still another object of my invention is to provide a plumber's clean-out with a cover having a locking lug attached in a novel 25 manner to the body of the cover, whereby the body may be of cast iron and the lug of less brittle material to avoid the liability of breakage in use.

A further object of my invention is to 30 provide a plumber's clean-out of the type employing a ring and a cover therefor in which the ring is provided with an inclined flange adapted for engagement with a lug of softer material on the cover, whereby upon the 35 tightening of the cover, the flange of the ring will slightly cut or abrade the lug, so as to effect a tight and secure engagement between the lug and flange.

Still another object of my invention is to 40 provide in a clean-out of the kind described a resilient gasket between the cover and ring, whereby the cover may be easily loosened without danger of breaking it.

The novel features of my invention are 45 hereinafter fully described and claimed.

In the accompanying drawing, which illustrates the preferred embodiment of my invention,

Figure 1 is a view, partly in elevation and 50 partly in vertical section of a drain pipe provided with my improved clean-out.

Fig. 2 is an enlarged cross-section on the line 2—2 of Fig. 1.

Fig. 3 is a longitudinal central vertical 55 sectional view on the line 3—3 of Fig. 2.

Fig. 4 is a longitudinal sectional view on the line 4—4 of Fig. 3.

Fig. 5 is an enlarged perspective view of one of the locking lugs of the cover.

Fig. 6 is an enlarged fragmental vertical 60 sectional view.

Similar reference characters designate similar parts in the different views.

The clean-out is provided with a ring 1 having a peripheral annular flange 2 at its 65 inner end and adapted to be calked in the usual manner in the clean-out opening of an ordinary drain pipe 3.

The ring is preferably tapering, its outer side converging outwardly, so as to permit 70 the calking 4 to be readily inserted and easily driven into its proper position against the flange 2.

5 designates the body of a cover having two lugs 6, preferably disposed diametrically 75 opposite each other and which are adapted to respectively lockingly engage the inner inclined sides respectively of two flanges 7 provided on the inner wall of the ring 1 adjacent to the outer end thereof. 80

The flanges 7 are spaced apart at their ends so as to permit of the insertion between them of the lugs 6, whereby the latter may engage the inclined inner sides of the flanges when the cover is turned to the locking position shown in Figs. 2 and 3. 85

There is preferably inserted between the ring 1 and body 5 a resilient gasket 8 which is adapted to be clamped between the cover and the outer edge of the ring 1. By having 90 the gasket 8 of resilient material, such as soft rubber, or leather, the cover may be struck with a hammer or wrench to force the cover toward the ring for the purpose of loosening the lugs 6 from engagement with 95 the flanges 7, without liability of breaking the cover.

In order that the clean-out may be cheaply manufactured, the ring 1 and the body 5 of the cover are preferably of cast iron. 100

In order that the lugs 6 shall not be liable to breakage, they are, preferably, of material softer than cast iron and less brittle. The lugs are preferably composed of an alloy, such as brass, which has sufficient 105 strength for the purpose and which is not liable to rust or stick to the flanges 7. By having the lugs 6 of brass or other material, which is softer than the flanges 7, upon tightening the cover, the flanges slightly cut 110

or abrade the lugs 6, thus permitting the lugs to more firmly engage the flanges than would be the case if the lugs were also cast iron.

5 In order that the lugs 6 may be firmly secured to the body 5, each lug is provided with a shank 9 provided, preferably, with a peripherally grooved portion 10 which is embedded in the body 5, the latter, in the 10 process of construction being cast around the shank of the lug.

By having the shank peripherally grooved, the lug is held firmly in its operative position and is not liable to be drawn therefrom 15 by the pressure of the lug upon the flange with which it engages. By having the shank 9 substantially of the same size at its inner and outer ends and transversely grooved, the body 5 is interlocked with the 20 lug, while at the same time, this shape of the shank permits of the ready removal of the patterns from the sand in the operation of molding the cover.

The outside of the cover is provided centrally with the usual square lug 11 with 25 which the cover may be gripped with a wrench.

In the operation of my invention, the cover is slipped over the outer end of the 30 ring 1 in a position at right angles to that shown in the drawing, and the cover is then turned to the position shown in Fig. 2, in which position the lugs 6 will respectively slide into engagement with the inclined 35 inner sides of the flanges 7. Upon applying a wrench to the square lug 11, the resilient gasket 8 will be tightly clamped between the cover and the ring.

Owing to the yielding and resilient nature of the gasket 8, if the cover has a tendency 40 to stick to the ring 1, after having been locked, it may be loosened safely by striking its outer side, so as to force the lugs 6 inwardly out of tight engagement with the flanges 7. The cover may then be retracted 45 to the position at right angles to that shown in Fig. 2, and withdrawn from the ring.

As noted in Fig. 6, the outer end of the ring 1 has a beveled periphery 12 and an annular inwardly extending portion 13, 50 whereby the gasket 8 will bear at its center against the ring 1 instead of at its outer edge. This will prevent liability of leakage. It will also be noted that the peripheral flange 14 of the cover engages the outer side 55 of the ring 1 at the outer side of the beveled periphery 12, so that the gasket and cover will be retained concentric with the ring.

I do not limit my invention to the structure shown and described, as modifications, 60 within the scope of the appended claim, may be made without departing from the spirit of my invention.

What I claim is:—

In a plumber's clean-out, a cover comprising 65 a cast body and a locking lug of softer material than the body, the lug having an outwardly extending arm spaced apart from the body, so that a locking flange may be received between the lug and the body, the 70 lug having a shank at right angles to the arm, the shank having a peripheral groove portion embedded in the body.

In testimony whereof I have signed my name to this specification.

ROBERT CLOW.
